UNITED STATES PATENT OFFICE

2,012,729

DEVICE FOR IMPARTING ROTATING MOTION TO TOYS

Albert C. Pisacano, Yonkers, N. Y.

Application September 29, 1934, Serial No. 746,126

6 Claims. (Cl. 46—32)

The invention relates to a device by means of which a spinning or rolling toy may be rotated and from which the toy may be released so as to spin or roll by itself. It has for its main object to provide a device which can be used with a great many toys of this type and in which the release may be positively and practically instantaneously effected without slowing down the speed which has been imparted to the toy. Another object is to provide a device which can be used with such toys without the exercising of any great skill in attaching it or in manipulating it. A further object is to provide a device of very simple and inexpensive construction.

This and various other objects and advantages will be readily understood from the following description and from the accompanying drawing of a preferred embodiment of the invention in which, however, modification may be made without departing from the scope of the invention.

In the drawing

Fig. 1 shows the device applied to a spinning top.

Fig. 2 is a side view, shown partly in cross-section and indicating the manner in which the top is released.

Fig. 3 is a top view of the top, and

Fig. 4 shows a view of one of the discs used with the device.

Referring now to all the views, simultaneously, in the present instance a spinning top 10, having a spindle 11 which extends to both sides of the disc, has been selected to illustrate the device. Two openings 12 and 13 are provided in the disc of the top.

The device itself consists of two side plates 14 and 15 to each of which a looped cord 16 and 17 is secured. The side plates are also provided with snap fastening members. In the present case the female parts 18 are shown attached to the plate 14, while the male parts 19 are shown attached to the plate 15.

When it is desired to impart rotary motion to the top, the snap fasteners are inserted through the openings 12 and 13 and snapped together so that the plates 14 and 15 are located on and clamped against each side of the disc of the top. Circular openings 20 being provided in the plates to accompany the ends of the spindle 11. If the operator now inserts his fingers in the outer loops of the cords 16 and 17 and twirls the top, the cords will be twisted as shown on the drawing. By alternately pulling on the cords and relaxing the pull a great speed may be imparted to the top, in the manner well known to the art.

When the required speed has been obtained, an additional pull on the cord will cause the snap fasteners to separate and thus release the top, as illustrated in Fig. 2. In this instance, the top will fall to the floor and roll along on its edge.

It will be seen, that if rotative motion is imparted to the top and the top and the cords are held as shown in Fig. 1 that when the top is released, it will alight on the end of its spindle and thus spin on the floor.

It will be evident to those skilled in the art that a great many different kinds of spinning and rolling toys may be used with this device. It will also be evident that, if the disc of the top is supplied with vanes or blades, it will soar up into the air when released, instead of falling to the floor. For these reasons it is not the intention to limit the device to any particular kind of top or toy, but to employ it with any device to which it may be found adaptable.

Having described my invention and its objects, what I claim as new and wish to protect by Letters Patent is:

1. In combination with a circular disc having a plurality of openings spaced equi-distant from its center, a pair of side plates, a looped cord secured to one side of each of said side plates, members of snap fastening devices secured to the other sides of said plates, said snap fastening members insertible through the openings in said disc and engageable with each other so as to clamp the disc while it is being rotated by the manipulation of the looped cords; the snap fastening members being of smaller diameter than the openings in the circular disc so that the disc is held solely by the clamping action of the side plates against its sides.

2. In combination with a circular disc having a plurality of openings spaced equi-distant from its center, a pair of side plates, a looped cord secured to one side of each of said side plates with its attached ends spaced a considerable distance apart, members of snap fastening devices secured to the other side of said plates, said snap fastening members insertible through the openings in said disc and engageable with each other so as to clamp the disc while it is being rotated by the manipulation of the looped cords; the snap fastening members being of smaller diameter than the openings in the circular disc so that the disc is held solely by the clamping action of the side plates against its sides.

3. In combination with a spinning top having a spindle and a body member provided with a plurality of openings, a pair of side plates, one of

said plates having a central opening for accommodating the spindle of the top, a looped cord secured to one side of each of said side plates, members of snap fastening devices secured to the other side of said plates, said snap fastening members insertable through the openings in said body member and engageable with each other so as to clamp the top while it is being rotated by the manipulation of the looped cords; the snap fastening members being of smaller diameter than the openings in the spinning top so that the top is held solely by the clamping action of the side plates against its sides.

4. In combination with a spinning toy having a double ended spindle and a body member provided with a plurality of openings, a pair of side plates, said side plates having central openings for accommodating the ends of the spindle of the toy, a looped cord secured to one side of each of said side plates, members of snap fastening devices secured to the other side of said plates, said snap fastening members insertable through the openings in said body member and engageable with each other so as to clamp the toy while it is being rotated by the manipulation of the looped cords; the snap fastening members being of smaller diameter than the openings in the spinning

toy so that the toy is held solely by the clamping action of the side plates against its sides.

5. In combination with a circular disc having a plurality of openings placed equi-distant from its center, a pair of side plates, a looped cord secured to one side of each of said side plates, means for clamping the side plates against the sides of the disc, said means being insertable through the openings in the circular disc and being separable by a pull on the cords, and said means being of smaller size than the openings in the disc so that the disc will be held by the clamping action of the side plates only. 5

6. In combination with a spinning top having a plurality of openings placed equi-distant from its center, a pair of side plates, said side plates having central openings for accommodating the spindles of the top, a looped cord secured to one side of each of said side plates, means for clamping the side plates against the sides of the top, said means being insertable through the openings in the top and being separable by a pull on the cords, and said means being of smaller sizes than the openings in the top so that the top will be held by the clamping action of the side plates only. 10 20 25
